No. 814,906.

PATENTED MAR. 13, 1906.

J. L. GLEASON,
BOX FOR ELECTRIC MOLDINGS.
APPLICATION FILED JULY 10, 1905.

UNITED STATES PATENT OFFICE.

JOHN L. GLEASON, OF JAMAICA PLAIN, MASSACHUSETTS.

BOX FOR ELECTRIC MOLDINGS.

No. 814,906.

Specification of Letters Patent.

Patented March 13, 1906.

Application filed July 10, 1905. Serial No. 268,906.

To all whom it may concern:

Be it known that I, JOHN L. GLEASON, a citizen of the United States, residing at Jamaica Plain, in the county of Suffolk and State of Massachusetts, have invented new and useful Improvements in Boxes for Electric Moldings, of which the following is a specification.

The object of this invention is to provide a cheap, simple, and convenient box for joining together, covering, and clamping to supporting-walls moldings for electric wires and for inclosing and protecting the portions of said electric wires which extend from one molding to another.

The object is further to connect together the ends of two moldings, each having two wires therein to a molding having three wires therein, one wire from each of said two-wire moldings extending therefrom through said box into said three-wire molding, and the other two wires from said two-wire moldings extending into said box and spliced to the third wire, which extends into said box from said three-wire molding.

The object is further to clamp the covers of said moldings each to its respective molding and to clamp the moldings themselves together with said covers to a ceiling and wall, said ceiling and wall located substantially at right angles to each other.

The invention consists in the combination and arrangement of parts set forth in the following specification, and particularly pointed out in the claims thereof.

Referring to the drawings, Figure 1 is a perspective view of my improved reduction-box with a portion of a vertical three-wire molding and cap projecting thereinto and with a portion of two horizontal two-wire moldings also projecting thereinto. Fig. 2 is a perspective view looking downwardly upon my improved box, illustrating the two-wire moldings and three-wire molding projecting thereinto, and also illustrating the wires projecting from said moldings into the interior of said box, one wire from each of the two-wire moldings being connected to two wires projecting into the interior of the box from the three-wire molding, while the third wire from said three-wire molding is spliced to two wires extending from said two-wire moldings. Fig. 3 is a front elevation of my improved box with the two-wire and three-wire moldings hereinbefore referred to illustrated in connection therewith.

Like numerals refer to like parts throughout the several views of the drawings.

In the drawings, 5 is my improved box consisting of two end plates 6 and 7, said end plates each having two straight sides 8 and 9 at right angles to each other, while the front edge 10 of each of said end plates is curved, said end plates being integral with and joined together by a curvilinear front plate 11. The front plate 11 has a recess 12 in its lower edge and a recess 13 in its upper edge, the recess 13 being larger than the recess 12. The recess 12 is provided with a longitudinal side 14, which is connected to the ends 15 and 16 of said recess by bevel corners 17 and 18, respectively. The longitudinal side 19 of the recess 13 is connected to the ends 20 and 21 of said recess by bevel corners 22 and 23, respectively, and midway of the longitudinal side 19 of said recess 13 is a V-shaped projection 24.

Horizontal flanges 25 project from the upper edge of the front plate 11 and vertical flanges 26 project downwardly from the lower edge of said front plate. These flanges are provided with screw-holes 27 in order that the box may be clamped against the moldings, and thus clamp said moldings against the walls and ceiling, as hereinafter described.

The three-wire molding 28 projects into the recess 12. Said molding is provided with three grooves 29, in which are located wires 30, 31, and 32. A cap 33 is provided to cover said grooves and wires, and said cap is clamped against the front face of the molding 28 by the bevel corners 17 and 18, which bear against the opposite front edges of said cap, respectively, and clamp said cap to the front face of the molding and also clamp said molding against the vertical wall of the room, when said box is fastened to said wall by means of screws extending through the holes 27, provided in the flanges 26.

Two two-wire moldings 34 and 35, located side by side, project into the recess 13, each of said moldings being provided with two grooves 36 and 37, respectively, and with wires 38, 39, 40, and 41. Caps 42 and 43 are provided for the moldings 34 and 35, respectively, and said caps are clamped against the moldings by bevel corners 22 and 23, respectively, said caps being further clamped against said moldings by the V-shaped projection 24, and both caps and moldings are clamped against the ceiling, when said box is fastened to said ceiling by

means of screws projecting through the holes 27 27 in the flanges 25 25. By reference to Fig. 2 it will be seen that the wire 30 is connected to the wire 38, the wire 32 to the wire 41, and that the wire 31 is spliced to the wires 39 and 40. The inner ends of the moldings and of their caps project into the hollow interior of the box 5, and the ends of the wires 30, 31, 32, 38, 39, 40, and 41 project also into said interior, where they are conveniently spliced together, said wires being thoroughly protected when the box is in position by the box, as illustrated in Fig. 1.

It will be seen that my improved box not only serves as a means for connecting together the moldings and for clamping said moldings to the ceiling and to the walls, but also acts as an effectual protecting means or cover for the wires where they extend from one of said moldings to the other.

Having thus described my invention, what I claim, and desire by Letters Patent to secure, is—

1. A reduction-box for electrical moldings comprising in its construction two end plates joined together by a curvilinear front plate, integral therewith, said front plate provided in each of its opposite edges, respectively, with a recess, one of said recesses being larger than the other, said recesses each having two ends connected by a longitudinal side, and a beveled corner connecting each of said ends to said sides at opposite ends thereof, respectively.
2. A reduction-box for electrical moldings comprising in its construction two end plates joined together by a curvilinear front plate, integral therewith, said front plate provided in each of its opposite edges, respectively, with a recess, one of said recesses being larger than the other, said recesses each having two ends connected by a longitudinal side, and a beveled corner connecting each of said ends to said sides at opposite ends thereof, respectively.
3. A reduction-box for electrical moldings comprising in its construction two end plates joined together by a curvilinear front plate, integral therewith, said front plate provided in each of its opposite edges, respectively, with a recess, one of said recesses being larger than the other, said recesses each having two ends connected by a longitudinal side, and a beveled corner connecting each of said ends to said sides at opposite ends thereof, respectively.

beveled corner connecting each of said ends to said sides at opposite ends thereof, respectively, and a V-shaped projection extending 45 into the larger of said recesses from said longitudinal side, midway between said corners.

3. A reduction-box for electrical moldings comprising in its construction two end plates joined together by a curvilinear front plate, 50 integral therewith, said front plate provided in each of its opposite edges, respectively, with a recess, one of said recesses being larger than the other, and flanges projecting from the longitudinal edges of said front plate substantially at right angles to each other.

4. A reduction-box for electrical moldings comprising in its construction two end plates joined together by a curvilinear front plate, integral therewith, said front plate provided 60 in each of its opposite edges, respectively, with a recess, one of said recesses being larger than the other, said recesses each having two ends connected by a longitudinal side, and a beveled corner connecting each of said ends 65 to said sides at opposite ends thereof, respectively, and flanges projecting from the longitudinal edges of said front plate, substantially at right angles to each other and fastened to two supporting-walls at an angle to each 70 other; in combination with moldings projecting into said recesses and caps for each of said moldings, said beveled corners bearing against the edges of said caps, whereby said caps are clamped against said moldings, and 75 said moldings are clamped against said supporting-walls.

In testimony whereof I have hereunto set my hand in presence of two subscribing witnesses.

JOHN L. GLEASON.

Witnesses:

CHARLES T. GOODING,
ANNIE J. DAILEY.
